UNITED STATES PATENT OFFICE.

JAMES F. MAYS, OF BIRMINGHAM, ALABAMA, ASSIGNOR TO MAYS ACCOUNTING MACHINE COMPANY, OF ASHEVILLE, NORTH CAROLINA, A CORPORATION OF NEVADA.

CALCULATING-MACHINE.

1,220,665.

Specification of Letters Patent.

Patented Mar. 27, 1917.

Application filed March 19, 1914. Serial No. 825,876.

To all whom it may concern:

Be it known that I, JAMES F. MAYS, a citizen of the United States, residing at Birmingham, in the county of Jefferson and State of Alabama, have invented certain new and useful Improvements in Calculating-Machines, of which the following is a specification.

This invention has for its objects broadly 10 the production of a calculating machine capable of performing arithmetical operations in the simplest and most direct manner; which shall be dependable and accurate in operation, light and portable in character, 15 and simple in construction; which shall be capable of operation by a comparatively light finger touch, and which shall be readily used with a typewriter or independently thereof.

20 With the foregoing general objects in view, this invention embodies a keyboard and registering dial arrangement whereby the operations of subtraction and division particularly may be performed in a very 25 much more direct and simple way than ever before on a calculating machine as far as I am aware; it embodies novel mechanism whereby the operation of registering dials is effected in a direct and simple manner and 30 whereby overthrow of such dials both in operation from their respective keys and in carrying is positively prevented; it provides a novel resetting mechanism and means for preventing overthrow of the dials in resetting, 35 and means to unlock the dials for resetting and relocking them after resetting; it provides auxiliary or floating dials for the purpose of registering totals or verifying results of operations of other dials; it 40 provides means for preventing the accidental displacement of said floating dials when set free; it provides a series of dial shaft units each comprising a rotatable dial operating shaft, one or more registering 45 dials thereon, and carrying mechanism individual to each of said shafts, each of said units being separately liftable out of the machine; it also provides a novel arrangement for supporting the carrying mechanism of the respective dial operating shafts 50 whereby the shafts themselves are entirely

free from the weight and friction of such mechanism, and a like arrangement with respect to the floating dials, and it also provides a novel mechanism for the operation 55 of a typewriter from the keys of the calculating machine, and other features, all of which will be better understood from the following detail description of a specific embodiment of the said invention, in which description reference will be had to the accompanying drawings wherein:

Fig. 1, represents a top plan view of the calculating machine detached from a typewriter;

Fig. 2, a vertical section taken through that portion of the machine indicated by the line 2x—2x Fig. 7, looking from front to rear of the machine;

Fig. 3, a longitudinal vertical section of 70 the machine shown in Fig. 1, with the outer casing removed, and on a larger scale than Fig. 1;

Fig. 4, a fragmentary detail section of the tension mechanism for the master rock 75 shafts;

Fig. 5, a fragmentary detail view partly in section and partly in top plan, showing the arrangement for guiding the upper portions of the key stems;

Fig. 6, an enlarged fragmentary detail top plan view of portions of the dial shaft actuating and carrying mechanism;

Fig. 7, a fragmentary section on line 7x—7x Fig. 3, looking down;

Fig. 8, represents in development one of the addition dials, one of the floating dials, and one of the complementary dials, showing the relative arrangement of the numbers on these dials;

Fig. 9, a fragmentary detail elevation partly in section, of the gearing connecting the several dial shafts with the carrying mechanism of the dial shaft of the next higher denomination, for tensioning the motion impelling elements of the respective carrying mechanisms;

Fig. 10, a detail sectional elevation of the mechanism for restraining and releasing the carrying mechanisms of the respective dial shafts;

Fig. 11, a fragmentary detail sectional ele-

vation primarily to show the mechanism for preventing overthrow of the dial shafts when operated by their respective keys;

Fig. 12, a detail sectional elevation of the 5 overthrow, locking and lock releasing mechanism of the carrying mechanism for a given dial shaft;

Fig. 13, a detail perspective view of the locking lever shown in Fig. 12;

Fig. 14, a side elevation of the machine 10 shown in Fig. 1, with a portion of one corner broken away;

Fig. 15, a detail sectional elevation showing 15 the coupling operating lever of the reset mechanism, together with related parts;

Fig. 16, a fragmentary detail section on 20 line 16^x—16^x, Fig. 15, and showing in top plan a portion of the lock operating mechanism controlled by the lever shown in Fig. 15;

Figs. 17, 18 and 19, are fragmentary detail sections taken on lines 17^x—17^x, 18^x—18^x and 19^x—19^x, Fig. 15;

Fig. 20, a detail longitudinal section 25 through the handle of the reset lever;

Fig. 21, an enlarged fragmentary detail section taken on line 21^x—21^x Fig. 3, looking toward the front of the machine;

Figs. 22 and 23, fragmentary detail sections 30 elevations of portions of the dial shaft locking and releasing mechanism operated in connection with resetting the dials;

Fig. 24, a fragmentary detail section on 35 line 24^x—24^x Fig. 21, looking down;

Fig. 25, a detail sectional elevation, showing 40 the arrangement of the spring against which the reset operating shaft shown in Figs. 22 and 23 is located;

Figs. 26 to 33, inclusive, details of the 45 division counter or quotient registering mechanism;

Fig. 34, a front elevation showing the calculating machine coupled to a typewriter;

Figs. 35 and 36, detail views of the mechanism 45 for holding the typewriter and calculating machine in proper alignment;

Fig. 37, a horizontal section through the lower portion of the typewriter frame, showing the typewriter operated mechanism 50 thereunder in top plan, and also showing in fragmentary top plan the calculating machine connected to this mechanism;

Fig. 38, a detail section on line 38^x—38^x Fig. 37, looking to the left;

Fig. 39, a detail section on line 39^x—39^x, Fig. 37, looking to the left, with the lower 55 portion of the typewriter removed;

Fig. 40, a detail section on line 40^x—40^x Fig. 37, looking toward the rear of the machine, and

Fig. 41, a detail vertical section through 60 the inner casing of the calculating machine, with many parts removed, to show the relation between the key stems and the typewriter operating rock shaft levers, as well as 65

the way of supporting the shiftable frame carrying said shafts and levers.

The machine here shown comprises among other parts, a series of columns of keys 1, having finger tips upon which appear the digits represented by the respective keys according to the usual practice in machines of this class. In the accompanying drawings seven columns of these keys are shown, but any desired number of columns may be employed.

Each key is provided with a stem 2 consisting preferably of a flat metal bar of rectangular cross-section. These keys are mounted for vertical reciprocating motion, and for the purpose of holding their stems in an upright position and guiding their vertical movement there is provided for each column of keys a guide plate 3 having a series of open end slots 4 of a depth corresponding approximately to the width of the key stems, and each of these slots receives an individual key stem vertically movable therein. The key stems are retained within slots 4 by plates 5. Plates 3 and 5 are removably secured, as by screws 6, to the frame of the machine as shown in Figs. 3 and 5.

The key stems are guided below by a plate 7 fast to the machine frame and having openings through which the individual key stems extend.

Each key is at all times under tension upward of an individual coil spring 8 attached at one end to the key stem, and at 100 its other end to the plate 3 through which the key stem passes. The upward travel of each key is limited by a stop 9 on its stem engaging that one of the plates 3 through which the stem passes.

For each column of keys, there is an individual master rock shaft 10 extending through and journaled for rotation in two supports 11 and 12 which are made fast to the sides 13 and 14 of a casing having ends 110 15 and 16. This casing is rectangular in horizontal cross-section, and constitutes what may be called the main frame of the machine. An outer casing fits over this inner casing or frame and will be described in 115 greater detail later.

The sides and ends of the inner casing or frame may be made integral with each other, but the supports 11 and 12 are preferably removably attached by screws or otherwise to the sides 13 and 14.

Each shaft 10 is rotatable on its longitudinal axis by any of the keys of its corresponding column, said motion being imparted to said shafts by the engagement of gear teeth 17 on the several key stems, with individual sector gears 18 fast on the rock shafts.

Keys 1 are all intended to travel down the same distance when operated, but each 130

- key in a given column must rotate its shaft 10 a different amount in order to properly actuate certain number bearing dials hereinafter more particularly described. In 5 other words, the "1" keys must turn their dials 10 one-tenth of a revolution; the "2" keys must turn the same dials two-tenths of a revolution; the "3" keys must turn said dials three-tenths of a revolution, and so on. 10 This is effected by the proper location of the teeth 17 on the several key stems so as to engage with their sectors 18 at the proper time. In Fig. 11 a "3" key is shown, in which case the key stem has three gear teeth 15 so located as to commence to engage with sector 18 when the key has reached six-tenths of its travel down.

The zero keys of the calculating machine are merely for the purpose of printing zero 20 on a typewriter, as hereinafter described, and have no connection with the rock shafts 10.

Each of said rock shafts is rotated, as described, against the tension of an individual 25 spiral spring 19 fast at one end to the shaft, and at its other end to a ratchet 20 recessed to receive said spring. (See Fig. 4.) These ratchets are each normally held 30 against rotation by a pawl 21 pivoted on supporting bar 12. The tension of spring 19 may therefore be readily adjusted by adjusting the angular position of the ratchets 20. The end 16 of the inner casing is made low to permit ready access to the ratchets. 35 For each rock shaft 10 there is a corresponding dial shaft 22 operated thereby. In the accompanying drawings, Fig. 7, but five of these dial shafts are shown, it being understood that in actual practice in this machine there would be seven such shafts, or 40 as many as there are columns of keys.

The shaft 23 is an extra dial shaft provided for purposes which will hereinafter more fully appear.

45 All of these dial shafts rest at their opposite ends in bearings in the end 15 of the inner casing or frame, and in a plate or bar 24 made fast to supporting plate 11. Parts 15 and 24, however, form bearings for only 50 the lower half of said shafts, the upper half of said bearings being formed by two bars 25 and 26 screwed to the top of the portion 15 of the machine frame and to the top of the supporting bar 24, respectively. (See 55 Fig. 3). This form of bearing is provided to permit the dial shafts, together with the parts carried thereby, to be readily removed separately as units for repairs or for replacement by other dial shaft units.

60 Each of the dial shafts 22 carries two number dials 27 and 28 fast thereon. Dials 27 constitute the regular adding and multiplying dials and each has upon its periphery a similar series of numbers from zero to 9 65 inclusive, said numbers on the several dials

27 occupying corresponding angular positions according to the usual practice in dial indicating adding or calculating machines. Dials 28 constitute division and subtraction dials and each bears upon its periphery 70 numbers from zero to 9 inclusive, but these are in complementary arrangement with respect to the numbers on the dials 27. That is to say, for each number on a dial 27, the complement of that number on the basis 75 of nine occurs in a corresponding angular position on dials 28, as will be readily seen from Fig. 8 which shows two of the dials 27, 28 in development.

In the following description, for convenience, dials 28 will be referred to as "complementary" dials.

In addition to the above mentioned dials there is provided a set of auxiliary or floating dials 29, one for each shaft 22, and these 85 dials, while being rotatable by said shafts are not actually mounted thereon in the sense of being supported thereby. Each dial shaft 29 has an elongated sleeve hub 30 which is rotatable in a bearing 31 carried by a shifting bar 32 which is movable, as hereinafter described, longitudinally of the dial shafts. The dial shafts pass through the sleeve hubs of dials 29, but do not touch them, thereby relieving said shafts 95 of all friction due to engagement with said dials as well also as the weight of the dials themselves.

As shown, these auxiliary dials 29 are provided primarily for the purpose of verifying an amount that has been printed on a typewriter through the operation of the calculating machine keys, though they may be used for totaling or any other desired purpose. Broadly their purpose may be 100 stated as that of registering a result obtained on the other dials, and holding this result while the calculating machine keys are being operated to obtain another result or record in printing the amount registered 105 on said auxiliary dials.

A specific operation will be gone through later on in this description, involving these auxiliary dials, when the function and utility will be more apparent.

115 Bearings 31 are flattened on two sides (see Fig. 2) to fit square openings 33 in the shifting bar 32, and this bar is provided with a section 34 normally holding bearings 30 in place, but which may be removed to 120 permit lifting the dial shafts together with the parts carried thereby out of the machine separately.

Shifting bar 32 is supported at its ends upon flanges 35 and 36, on the sides of the 125 machine frame, engaging guide slots in the ends of bar 32.

The operation of dials 29 and the mechanism for shifting bar 32 longitudinally of the dial shafts for the purpose of cou- 130

pling them to said shafts will be taken up later.

Fast on each of the rock shafts 10 is an intermittent gear 37, and these gears are adapted to mesh respectively with pinions 38 on the dial shafts.

Pinions 38, however, are not positively connected to the dial shafts, but are connected thereto through clutches, each comprising a member 39 fast to or formed on the pinions 38, and a member 40 fast to its dial shaft. These clutch members are coupled by means of a spring pawl 41 on the member 39 engaging teeth 42 on member 40. (See Fig. 6.) Through this gearing and coupling, rotation is imparted to the dial shafts from their respective rock shafts 10.

For each rock shaft 10 there is a supplementary or auxiliary rock shaft 43 extending parallel thereto and journaled at one end in the end 16 of the machine frame, and at the other end in a bar 43^a extending transversely across the machine and secured at its ends to the sides 13 and 14 of the machine frame. Each of these auxiliary rock shafts carries a series of arms 44, each arranged to extend into the path of a pin 45 carried by each key stem. The pins 45 are so located that they will engage arms 44 just before the keys reach the lower limit of their travel; and as the keys continue their travel downward, said pins will cause the arms 44 to rock their shafts 43. One effect of this rocking of shafts 43 is to prevent overthrow of the dial shafts in the case where they are key operated as distinguished from operation by the carrying mechanism, and this is effected by the passage of the upper end of each of a series of stop levers 46 (see Fig. 11), into position to be engaged by the teeth of a stop ratchet 47, one of which ratchets is fast on each of the dial shafts 22. There is a stop lever 46 fast on each of the auxiliary shafts 43, and each of these shafts is under the tension of a spring 43^a normally pulling arms 46 against stops 46^a. (See Fig. 11.)

For the purpose of effecting carrying from one dial shaft to another, the following mechanism is provided: For each dial shaft except the units dial shaft or the first one on the right in Fig. 7, there is provided a gear 48 which is rotatable on a sleeve 49 removably mounted but normally held fast as hereinafter described in a supporting bar 50 made fast at its opposite ends to the sides of the frame of the machine. Each sleeve 49 is provided with a section flattened on two sides to fit into a square opening 51 in bar 50 (see Fig. 9), said sleeve being held firmly in said openings by a removable bar 52 screwed upon the top of supporting bar 50. Sleeve 49 may therefore be lifted out of the machine together with the parts which they carry.

The dial shafts pass through central openings in sleeve 49, but do not touch them, thereby relieving said shafts of the friction of these sleeves as well as the weight of them and the parts carried thereby.

Also mounted to rotate on each sleeve 49 is a carrying ratchet 53, and each of these ratchets is connected to a gear 48 on the same sleeve 49 therewith through a spiral spring 54 connected at one end to the ratchet, and at the other end to the said gear as shown most clearly in Fig. 7.

Rotation is imparted from each carrying ratchet 53 to its dial shaft through a clutch comprising a spring pawl 55 fast to the carrying ratchet and engaging with teeth 56 on a clutch member 57 fast to the dial shaft, as shown most clearly in the detail view Fig. 6.

Each gear 48 (see Fig. 9) meshes with a pinion 58 rotatable respectively on stud 85 shafts 59 fast in supporting bar 50.

Pinions 58 are driven by gears 60, which in turn mesh with pinions 61 fast on each of the dial shafts. By means of this train of gearing, springs 54 are wound up a certain amount on each forward rotation of any of the dial shafts. Said springs are, however, always under a certain amount of tension.

Gears 48 to 61 are so proportioned that it requires one full revolution of a given shaft 22 to impart $\frac{1}{10}$ of a revolution to the shaft 22 of the next higher denomination.

These springs at all times tend to rotate the dial shafts, except the units dial shaft, in a forward direction, but are normally prevented from doing so by holding pawls 62 (see Fig. 10) one of which is provided for each carrying ratchet 53, the said pawls being fulcrumed on a cross-bar 63 made fast at its opposite ends to the sides of the machine frame.

These holding pawls are normally pulled back each against a stop pin 64 by a light spring 65, and are tripped at the proper time to release their carrying ratchets, each by a pin 66 carried on each of the dial shafts 22 next on the right, and of a lower denomination of units. Pins 66 trip the holding pawls 62 between nine-tenths and a complete revolution of the dial shaft next on the right, thereby releasing the carrying ratchet and allowing its dial shaft to rotate one step or "carry one". Immediately after any stop pawl 62 is tripped, it returns to normal under the action of its spring 65 and stops its carrying ratchet at the end of one step.

For the purpose of preventing overthrow of the dial shafts in carrying, there is mounted fast on each such shaft, except the units dial shaft, a stop ratchet 67, and adapted to coöperate with each of these stop ratchets is a stop lever 68 of peculiar construction.

Each lever 68 is fast on an individual sleeve 69, and one of these sleeves is mount-

ed for rotation on each of the supplementary rock shafts 43. (See Fig. 3).

The construction of levers 68 may be best

seen in Figs. 12 and 13. Each of these 5 levers carries at its upper end a pivoted pawl 70 having a nose 71 adapted to engage the teeth of stop ratchet 67 and yieldable downward against the tension of a spring 72. The movement of pawl 70 on its pivot in a 10 clockwise direction, Fig. 12, is limited by a shoulder 73 on said pawl engaging a shoulder 74 on the arm 68. Each pawl 70 is also provided with an off-set lip 75 which is adapted to coöperate, as hereinafter 15 described, with a cam 76 on the next dial shaft 22 on the right of the one carrying the stop pawl 67 with which a given pawl 70 operates.

Each stop lever 68 is at all times under 20 tension toward its stop ratchet of an individual spring 77, its movement in said direction being limited by an arm 78 fast on sleeve 69, engaging with a cam 79 on one face of intermittent gear 37.

25 When any dial shaft 22 is in the normal or zero position, its cam 76 will occupy the position shown in Fig. 12.

As a given dial shaft 22 rotates either by 30 the operation of its corresponding keys or by the carrying operation from the next dial shaft on the right, its cam 76 will rotate with it in the direction of the arrow Fig. 12. In thus rotating, cam 76 acts upon lip 75 to rotate arm 68 away from ratchet 35 67, thus removing nose 71 from the path of the teeth of ratchet 67 in time to allow shaft 22, on which said ratchet is fast, to rotate in performing the carrying operation. Cams 76, however, are so shaped and 40 adjusted on their shafts that immediately before the carrying operation is performed from its shaft 22 to the next one on the left, the drop of cam 76 will pass lip 75, allowing nose 71 of the stop pawl to return quickly to 45 the path of the teeth of ratchet 67 under the pull of spring 77. When nose 71 is thus returned and before ratchet 67 starts to rotate in the direction of its arrow (Fig. 12) to perform the carrying operation, shoulder 50 73 of pawl 70 will be in engagement with shoulder 74, and nose 71 will be in its "up" or raised position. Then, when ratchet 67 rotates in the direction of its arrow (Fig. 12) to "carrying," a tooth of said ratchet 55 will strike nose 71, but said nose will yield downward until it strikes stop shoulder 74 on arm 68, when the movement of ratchet 67 will be positively stopped. If nose 71 did not yield as described, it would be impossible 60 to insert said nose into the path of the teeth of the stop ratchet and at the same time allow ratchet 67 to rotate one-tenth of a revolution. The parts are so arranged that the noses 71 make positive contact with their

respective shoulders 74 precisely at the end 65 of one-tenth of a revolution of the dial shafts.

Lever 78 and cam 79, while above mentioned merely as stops for lever 68, are provided primarily for the purpose of withdrawing noses 71 from ratchet 67 when the dial shafts of those ratchets are operated directly by their own keys, as contra-distinguished from the carrying operation. In the former case whenever rock shaft 10 75 is rotated by any of its keys, this rotates gear 37 counter-clockwise (Fig. 12). This in turn causes cam 79 to force the upper end of lever 78 to the right, and as this lever is fast on sleeve 69 with arm 68, the latter will 80 be rotated in a clockwise direction Fig. 12, thereby removing nose 71 from ratchet 67. Intermittent gears 37 and 38 are so arranged that they do not intermesh until cam 79, acting upon lever 78, has removed stop 85 lever nose 71 from ratchet 67.

For the purpose of registering on dials 29 the results obtained on dials 27 or 28, there is provided means for coupling dials 29 to their respective dial shafts, and uncoupling 90 them from said shafts, at will. Such means comprises, in the machine here shown, a clutch for each dial 29, consisting of a series of teeth 80 on the sleeve hub of such dial, and a series of teeth 81 on the hub of the 95 dial 28 on the same shaft therewith. These teeth are coupled and uncoupled by the shifting of bar 32, and this is effected through the operation of levers 82, each having a bifurcated upper end 83 adapted to 100 engage opposite sides of bar 32, said lever being fast on a rock shaft 84, operable by a lever 85 fast thereon and located outside of the side 13 of the machine frame. (See Figs. 1 and 2).

For the purpose of retaining the totaling dials against accidental or not intended angular displacement when they are uncoupled from dials 28, I provide a holding device (see Figs. 21 and 24) which comprises a shiftable plate 86 having a series of down turned lips or wings 87 each carrying a shoe 88 of felt or other suitable friction material which is at times automatically moved into engagement with the dials 29 110 115 to hold them against rotation. This plate 86 rests upon the upper edge of bar 34 and is guided for longitudinal movement by pins 89 on said bar engaging slots 90 in said plate, there being one such pin and slot near 120 each end of plate 86. Plate 86 is at all times under tension of a spring 91 tending to pull it to the left (Fig. 24) or in such direction as to remove shoes 88 from the dials. Motion is imparted to plate 86 in the direction of the arrow, Fig. 24, to automatically bring said shoes against the dials when said 125 dials are set free, by the engagement of a

bevel 92 on one end of plate 86 with a bevel 93 on the side of the machine. When plate 86 is shifted in the opposite direction, shoes 88 are removed from the dials 29 under the action of spring 91.

5 For the purpose of resetting the dials to normal, the following mechanism is provided, (see Figs. 2, 3, 7 and 21):

10 On each dial shaft there is a pinion 94 loose to both slide longitudinally and rotate thereon. Fast to each of these pinions are two disks 95 and 96 provided respectively with arms 97 and 98. These arms are adapted to engage respectively with 15 studs 99 and 100 on disks 29 and 27 on the same shaft therewith, and through the coupling thus afforded either of these disks may be rotated by the rotation of a pinion 94. Normally, however, both arms 97 and 20 98 are disconnected from the disks, as shown in Fig. 3, but may be brought into operation relative therewith by the shifting of the pinions longitudinally of the dial shafts as hereinafter described.

25 All of the pinions 94 mesh with a rack 101 mounted upon shoulder screws 102 carried by a shiftable bar 103, said screws passing through slots 104 in the rack 101 to permit longitudinal motion thereof.

30 Bar 103 is provided at its opposite ends with right angle extensions 105 and 106, each having a slot or guide-way engaging with elongated lugs or flanges 107 and 108 respectively, on the sides of the machine 35 frame, said flanges supporting said bar for movement longitudinally of the axes of the dial shafts.

For the purpose of shifting bar 103 as stated, the following mechanism is provided:

40 Mounted fast upon a rock shaft 109 extending transversely across the machine are two levers 110 and 111, the upper ends of which engage respectively with recesses in 45 extensions 105 and 106 of bar 103. (See Figs. 2 and 3). Lever 110 is connected by a link 112 to a hand operated lever 113 pivoted upon a shoulder screw 114 on the side 13 of the machine frame and located 50 outside thereof. Lever 113 is normally maintained in a vertical position so as to disengage arms 97 and 98 from the dials, by two pivoted dogs 115 and 116 (see Fig. 15) which bear, under the tension of a 55 spring 117, against opposite sides of a sleeve 118 on a shoulder screw 119 on lever 113 and extending through an opening 120 in the side 13 of the machine frame. Dogs 115 and 116 are pivoted on the inside of 60 the machine frame and are limited in their movement toward each other by stationary stop bar 121. It will be seen from this construction that lever 113 may be shifted in either direction, but each time against the 65 tension of spring 117 which, when the lever

is released, will return it to the central or normal position.

By shifting lever 113 backward, arms 98 may be brought into operative relation with pins 100 of the dials 27, or by shifting said lever forward or toward the operator, arms 97 may be brought into operative relation with pins 99 of dials 29.

To reset dials 28, arms 98 are brought into position to operate upon pins 100 of dials 27, since dials 27 and 28 are fast upon the same shafts.

After the arms 97 or 98 are shifted into operative relation with their respective dials as described, the dials are brought to their normal positions by the angular movement of said arms which in turn is effected through the rotation of gears 94 by the shifting of rack 101. This shifting is effected through the operation of a train of 85 gearing comprising, among others, a gear 122 meshing with teeth 123 cut on the lower edge of bar 101. Gear 122 is rotatable on a shoulder screw 124 carried by a downward extension of bar 103. Gear 122 meshes 90 with a broad pinion 125 which is mounted fast upon a shaft 126 journaled in a sleeve 127 supported in transverse supporting bars 128 and 129 secured to opposite sides of the machine frame. Also fast on shaft 126 95 is a miter pinion 130 which meshes with a miter gear 131 fast on a rock-shaft 132 journaled in the frame sides 13 and 14.

Pinion 125 is broad enough to allow the shifting of gear 122 parallel to the axis 100 of said pinion so as to bring reset arms 97 or 98 into operative relation with their respective dials without disengaging gear 122 from pinion 125.

Shaft 132 is at all times under tension of 105 a coil spring 133 secured at one end to the shaft, and at its other end to the side 13 of the machine frame. (See Fig. 25). Shaft 132 is rotated against the tension of this spring, to reset the dials, by a reset 110 lever 134 fast on one end of said shaft and outside of the outer casing of the machine, said lever being normally held by spring 133 against a stop pin 135.

The full forward movement of reset lever 115 134 is limited by a stop 136 on the outer casing of the machine. (See Fig. 14). In resetting the complementary or division dials to zero, this forward movement of the lever 134 should be only nine-tenths of its 120 full movement. For this purpose there is provided an auxiliary stationary stop 137 on the outer casing of the machine, arranged to stop the reset lever, when desired, at nine-tenths of its forward stroke, and, therefore, before it reaches stop 136. This is effected by causing auxiliary stop 137 to engage with a movable stop pin 138 carried by the handle 139 of the reset lever. Stop 138 (see Fig. 20) is formed on one end of 130

a plunger rod 140, the other end of which is fast to a cap 141, which makes a sliding fit over one end of handle 139. Rod 140 is slidable longitudinally in a bushing 142, 5 having chambers 143 and 144 at its opposite ends. Stop pin 138 extends into chamber 143 and is normally held against the bottom of said chamber, as a stop, by spring 145 in chamber 144, said spring tending at all 10 times to draw pin 138 into the handle and out of the path of stop 137.

When it is desired to have reset lever 134 stop at nine-tenths of its full stroke to reset the complementary or division dials, the 15 operator presses on the end of cap 141, causing pin 138 to protrude from the handle so as to engage auxiliary stop 137.

Before the dials can be reset, it is necessary to unlock the stop ratchets 67 by with- 20 drawing the nose 71 of each stop lever 68 from its ratchet. For this purpose the following mechanism is provided, (see Figs. 3, 15 to 19, and 22 and 23):

Lever 113 is provided with an extension 25 146 having a beveled portion 147 (Fig. 16) adapted to engage a beveled end 148 of a longitudinally slidable bar 149 supported near each end upon shoulder screws 150 (see Figs. 22 and 23) carried by a trans- 30 verse stationary bar 151 secured at its ends to the sides of the machine frame, said shoulder screws extending through slots 152 in bar 149 to permit the latter to slide longitudinally. Bar 149 is provided with a series 35 of downward extensions or lugs 153, one for each dial shaft, and each of these extensions carries a pin 154 adapted to engage each the forward edge of one of the levers 78. Therefore, when lever 113 is shifted backward to 40 couple gear 94 with the dials 27, cam 147 on said arm will shift bar 149 to the right (Fig. 16) and this in turn will cause pins 154, acting upon levers 78 to rotate sleeve 69 in a clockwise direction, which will with- 45 draw the noses of all the stop levers 68 from their ratchets 67 and thus set the dial shafts free to rotate for resetting.

Lever 113 is prevented from springing outward by a fixed shoulder screw 113^a (see Figs. 15 and 18) which passes through a slot 113^b in said lever.

Bar 149 is returned to normal by springs 77 acting through lever 68, sleeve 69, arms 78, and pins 154. Springs 77 at the same 55 time return stop levers 68 to their normal positions.

For the purpose of preventing overthrow of the dial shafts in resetting, mechanism is provided for throwing stop levers 46 into 60 locking relation with stop ratchets 47 when reset lever 134 is operated. Levers 46 are thus operated by a series of pins 155, one for each lever 46 carried by a bar 156 mounted to slide longitudinally upon shoul- 65 der screws 157 secured to frame plate 11

and extending through elongated slots 158 in bar 156. Bar 156 is shifted as stated by an arm 159 fast at its lower end on a rock shaft 160 to which is also made fast an arm 161. Fast on shaft 132 is an arm 162 so 70 positioned that before reset lever 134 has reached the end of its travel to reset the dials, arm 162 will engage arm 161 and rotate it downward, thereby rotating shaft 160 and causing arm 159 to move bar 156 to the left (Fig. 22) which causes pins 155 to send stop levers 46 into locking relation with stop ratchets 47. 75

Bar 156 remains shifted, as above described, until it is returned by levers 46 80 under the action of springs 43^a (see Fig. 11).

It is desirable to have an extra dial shaft and dials thereon for carrying only. For example, suppose the operator is adding two amounts, each containing as many figures as 85 there are columns of keys on the machine, and the sum of the two amounts contains more figures than there are columns of keys or regular dial shafts. Obviously, some means must be provided for registering the 90 extra figure. For this purpose there is provided, among other parts, an extra multiplication and addition dial 27^a, an extra totaling dial 29^a and an extra dial shaft 23 therefor provided with carrying mechanism, substantially the same as that of the other dial shafts, adapted to be operated by the next dial shaft 22 on its right. The shaft 23, however, has no corresponding column of keys and is therefore provided 95 with no mechanism for direct key operation. The dials 27^a and 29^a are similar in construction and are mounted similarly to dials 27 and 29, respectively, and are reset 100 in the same way as the other dials. Shaft 105 23, however, carries no complementary dial, the coupling of dial 29^a to said shaft being effected through a collar 28^a fast on said shaft and provided with teeth 81^a adapted to engage with teeth 80^a on the sleeve hub of 110 dial 29^a. (See Fig. 7.)

For use in performing the operation of division, this machine is provided with a quotient counter or register having a key or key bar located directly on the keyboard 115 of the machine, and which forms a part of said keyboard. This key bar in turn operates a series of counter wheels which display the numbers of the quotient on the keyboard so as to be readily viewed by the operator. 120

The mechanism of this counter is shown in detail in Figs. 26 to 33, inclusive, and comprises, in the case shown, a series of five counter wheels 163, each having ten teeth, and the back of each tooth bearing a number, these numbers running from zero to nine, inclusive. These wheels are all mounted side by side to turn on a common shaft 164 mounted rigidly on the supporting plate 165 made fast to side 14 of 130

the machine frame. While five wheels 163 are herein shown, I do not wish to be understood as limiting my invention to any particular number. Each counter wheel is recessed as at 166, and in each of these recesses is mounted a coil spring 167 attached at its inner end to shaft 164, and at its outer end to its counter wheel. Also rigidly attached to each counter wheel is a stop disk 168, each having a lug 169 which in the normal or zero position of each counter wheel is adapted to engage with a stationary lug or bar 170 on the machine frame. The tension of the springs 167 is such as to tend to rotate the counter wheels in a clockwise direction, Fig. 29, so as normally to hold lugs 169 against stop 170. These counter wheels are rotated step-by-step each by an individual actuating pawl 171, and these pawls are respectively pivoted to five slides 172 supported upon pins 173 and 174 attached rigidly to bar plate 165, and extending through slots 175 and 176 in the said slides. The pawls 171 are yieldable away from the counter wheels against the tension of individual springs 177 which normally hold them in the horizontal position shown in Fig. 29, each of said pawls being provided at its rear end with a square shoulder 178 adapted to abut against a shoulder 179 on its slide, and thus limit the movement of the pawls 171 toward the counter wheels.

Each counter wheel is provided with a holding pawl 180, pivotally mounted upon a stud shaft 180^a fast to plate 165, and each pawl is yieldable away from said wheels against the tension of individual springs 181.

Pivoted to each slide 172 at its end opposite pawls 171 is a latch 182, each of which is under pressure downward of an individual spring 183, the upward movement of each of these latches being limited by a shoulder 184 engaging a shoulder 185 on its slide. These latches travel in vertical slots 45 in a fixed guide bar 182^a. Common to all of these latches, for the purpose of operating the slides is an actuating bar 186 which forms a right angle extension on an arm 187 of a bell crank lever 188 pivotally mounted on an upward extension of the plate 165. A similar bell crank lever 189 is pivotally mounted on an upward extension of said plate, but is not provided with an actuating bar. Bell crank lever 189 is, however, provided with a downwardly extending guide arm 190 which moves between plate 165 and a guide plate 165^a secured to plate 165. Arm 187 is similarly guided by a plate 165^b. Levers 188 and 189 carry a key bar 191 flexibly mounted thereon, and this key bar is held in its normal position under the action of a spring 192 attached at one end to the depending arm of lever 188, and at its other end to plate 165^a.

For the purpose of raising latches 182

one at a time into operative relation with the actuating bar 186, there is located beneath each of these latches a lifting cam, said cams being indicated respectively by the numerals 193, 194, 195, 196 and 197, and all mounted upon a shaft 198, rotatably journaled in supporting plate 165. These cams are staggered angularly one-sixth of a circumference around the axis of their supporting shaft, and are fixed in this position on the shaft. Shaft 198 is rotated by a knob 199 fast thereon, and provided with six peripheral recesses 200, bearing numbers from zero to five inclusive, and corresponding in angular position to the setting position of the five cams 193 . . . 197 and a reset cam hereinafter referred to.

If it is desired to operate the counter wheels, knob 199 is turned so as to display the numeral "1" on top. This brings the setting cam 197 into the position shown in Fig. 29, when its latch 182 will be raised as shown. Then, each time the key bar 191 is struck, the actuating bar 186 will engage latch 182 and move its slide 172 to the right Fig. 29, causing pawl 171 attached to that slide to engage with its counter wheel and rotate the same one step, so as to display the numeral "1". The counter wheel corresponding to the latch 182 thus set, may be stepped around any number of times up to nine, depending upon the number of strokes given the key bar. If it be desired to set up the next figure of the quotient, knob 199 is turned one step so as to bring the next cam 196 into the vertical position, when it raises its corresponding latch 182 which may then be engaged by the actuating bar 186, and therethrough operate the next counter wheel in the series. When the second latch is raised, however, the first latch will descend out of operative relation with the actuating bar, due to the rotation of its lifting cam 197. In a similar way all of the figures of a quotient may be set up on the counter wheel.

For the purpose of resetting the counter wheels to zero, there is provided a releasing slide 201, supported upon pins 173 and 174 passing through slots 202 and 203 in said slide. This slide carries a cross-bar 204, fast thereon, which is adapted, on the operation of the releasing slide, to move all of the holding pawls 180 out of engagement with the counter wheels, thus releasing said wheels when they return to zero under the action of their respective springs 167. This reset slide is operated against the tension of a spring 201^a by a cam 205 fast on the setting shaft 198, and so angularly disposed thereon as to be brought into action against a depending extension 206 of slide 201 on the sixth step of setting shaft 198. For the purpose of accurately dividing the movements of shaft 198 into six equal steps, 130

- there is provided a correcting wheel 207 having six equally spaced peripheral notches, and these notches are adapted to engage one at a time with a holding spring 208 bent to conform with the contour of the said notches. When the setting shaft 198 is stopped in a position to reset the counter wheels, zero will be displayed on the top of actuating knob 199.
- 10 For the purpose of further preventing overthrow of knob 199 in turning it from one set position to another, and also for the purpose of serving as a marker in connection with the figures on the knob, there may be provided a thumb stop 209 made fast to the side of the machine and extending over a portion of said knob.
- 15 The inner casing or frame of the machine is provided with a suitable base 210 of wood, composition or other desired material, and secured to the lower face of this base are a series of preferably rubber knobs 211 upon which the machine rests. (See Fig. 14).
- 20 The entire inner casing or frame is enclosed in an outer casing 212 preferably of thin metal, and this outer casing is provided with suitable openings through its top for the levers 85, 113, 188, 189. The top of this casing is also provided with rows of openings through which are displayed the numbers on the dials 27, 27^a, 28, 29 and 29^a, and with an elongated opening for displaying a row of numbers on the quotient dials 163. There may be also secured to the top of this outer casing two stationary finger pieces 113^c and 113^d for use in operating lever 113. This arrangement contemplates the operation of lever 113 by placing one finger of the left hand on either of the stops 113^c or 113^d, and another finger on the handle of lever 113, and forcing the lever 113 in the direction of either finger piece 113^c or 113^d, according to the direction in which it is desired to operate said lever.
- 25 Also located on the top of the outer casing in front of the keys 1, are a series of pivoted decimal pointers 213, for each of which is provided a decimal point 214, which decimal points may be pins or merely dots painted on the casing. In addition to the decimal points 214, there may also be provided decimal indicating lines 215.
- 30 There is also provided a pivoted decimal pointer 216 for the quotient dials 163.
- 35 Appearing on the top of this outer casing to the left of keys 1, and in horizontal alignment, respectively, with horizontal rows of said keys, except the two upper rows, are a series of numbers 1 to 8. These are the complementary numbers; that is to say, they indicate which of the horizontal rows of keys 1 shall be struck to set up a number upon the complementary dials, and each of these numbers is the complement on the basis
- 40 of 9 of the number displayed on the key tops in the same horizontal line therewith. This arrangement is preferable to that commonly employed where the complementary numbers are placed on the same key tops as the regular numbers. It is more or less confusing to have two sets of numbers on the same keys even if they are in different colors. The complementary numbers on this machine, however, are preferably a different color from those on the keys.
- 45 The top of the outer casing is preferably made in two sections 217 and 218, the former section covering dials 27, 27^a, 28, 29, 29^a, their shafts and other inclosed mechanism forward of plate 11, while section 218 extends from line 218^a dividing the two sections rearward to the line 218^b. (See Fig. 1.) The rear end 219 of the outer casing is also preferably removable to afford ready access to ratchets 20 for adjusting the tension of the master rock shafts.
- 50 Casing sections 217, 218 and 219 are provided with flanges 220, 221 and 221^a, respectively, which fit over an extension or flange 212^a (see Fig. 21) soldered or otherwise made fast to the sides of the casing, and rests upon the edge of said sides.
- 55 By having the casing removable in sections, access to parts of the machine may be had without removing the whole casing or the whole top thereof. For example, by removing section 217 alone, access may be had to the dial shaft units and the parts forward of plate 11 without disturbing any other parts of the machine. With casing section 217 removed, any of the dial shaft units may be readily lifted from the machine, repaired and put back, or replaced by others.
- 60 The procedure in performing the operation of addition and multiplication of this machine does not differ essentially from that employed in operating other direct acting key operated machines, so need not here be gone into in detail. The digit keys 110 are merely struck according to the amounts, and the results are registered on the dials 27.
- 65 One way of performing the operation of subtraction on this machine is as follows:— Let it be required to subtract 254,236 from 738,625. First set the complementary dials 28 to zero. This is done by shifting lever 113 to couple the dial shafts to the reset mechanism and then pulling reset lever forward or toward the operator nine-tenths of a stroke, in which case cap 141 of the reset lever handle is pressed so as to cause stop pin 138 of said handle to protrude therefrom. Then, commencing with the sixth column of digit keys from the right, strike one key in each column proceeding from left to right, the numbers of the keys struck in the respective columns corresponding to complementary numbers 738,624 appearing on the top of the machine to the left of the

keys. This will set up 738,625 on the complementary dials. It will be noted that in the units column a key of a denomination one unit less than the last figure in the minuend was struck. This is done for the reason that there is no carrying into the last dial shaft operated.

The first dial 28 on the left will show the number 9, but this may be changed to zero by striking the 9 key in the first column on the left.

The next operation is to commence with the sixth column of digit keys from the right, and strike a key in each column, proceeding from left to right corresponding respectively to the digits 254,236 according to the regular numbers appearing on the key tops.

The answer will then appear on the complementary dials.

One way of performing the operation of division on this machine is as follows:

Let it be required to divide 25 into 9627. First, set all the complementary dials to zero, as described in connection with the operation of subtraction, and also set all of the quotient dials 163 to zero, if they are not already so set. Then, in the second column of keys from the left strike a key corresponding to complementary number 6. As the complementary dials are already set to zero, it is not necessary to strike a key for the figure 9 in the dividend. Next, strike a key in the third column from the left corresponding to complementary 2, and then in the fourth column of keys from the left strike a key corresponding to complementary 6. A number next lower than the last one in the dividend is struck for the same reason as stated in connection with the operation of subtraction. The complementary dials will then display 9627, reading from left to right, and these numbers are pointed off with the fourth decimal pointer 213 from the left.

Turn the second decimal pointer 213 from the left down so as to point off 96 on the complementary dials. Then strike key bearing number "2" in the left hand column and the key bearing number "5" in next to the left hand column and repeat this operation watching the complementary dials on the left of the decimal point, and each time that the keys bearing number "2" and "5" are struck run the hand over and strike the quotient registering bar 191. When the number on the complementary dials on the left of the decimal point registers below 25, stop striking keys "2" and "5". The quotient register will then show the numeral 3, which will be the first figure of the quotient. Move the next decimal pointer to the right down and turn the division counter knob 199 one step. Then strike the key in the second column from the left, bearing

the numeral "2", and strike the key in the third column from the left bearing the number "5" and repeat this operation, each time striking the quotient counter bar 191, until the numbers on the complementary dials on the left of the decimal point now used show less than 25. The quotient counter will then register 38. The next decimal pointer 213 on the right is then turned down and the quotient counter knob 199 rotated one more step. Repeat the same operation as before, but operating upon keys "2" and "5" of the third and fourth columns from the left. The quotient counter will then register 385, which is the number of times 25 will go into 9627, with a remainder of 2 showing on the complementary dials. To obtain this fraction in decimals, point off the numbers 385 on the quotient counter with decimal pointer 216, and turn down another decimal pointer of the series 213, and also turn knob 199 one step. The remainder on the complementary dials on the left of the last decimal pointer turned down will now show 20, but as 25 will not go into 20, the next decimal pointer 213 on the right of the last one operated is turned down when the remainder, as shown on the complementary dials, will be 200. Turn quotient counter knob 199 another step and then operate keys numbers "2" and "5" in the fourth and fifth columns from the left, and each time strike quotient counter 191. Continue this operation until the remainder shown by the complementary dials becomes less than 25, when the quotient dials will show 385.08.

The foregoing is the procedure where the operator desires to reset the complementary dials to zero before setting up the numbers thereon. The operations of subtraction and division may be performed without resetting said dials to zero to start with, in which case, they are left at "9", and in setting up the minuend and dividend it is not necessary to strike a key for the last figure of a denomination one less than that figure. If there are any superfluous nines left standing on the complementary dials after the number is set up, these may be brought to zero by striking the "9" keys in columns corresponding thereto.

For the purpose of operating a typewriter from the keys of the calculating machine, the following mechanism is provided:

This mechanism comprises, among other parts, a series of transverse rock shafts 222, one for each horizontal row of keys on the calculating machine, journaled in a rectangular frame 223 within the lower portion of the calculating machine frame and shiftable horizontally transversely of said machine. Frame 223 is supported upon pins 224 and 225 (see Fig. 41), the former slidably in openings in side 13 of the main

frame of the machine, and the latter in elongated bushings on sleeves 226 fixed to side 14 of said main frame. Fast on each rock shaft 222 is a series of levers 227, one 5 for each key of the machine, each such lever having an upwardly extending free end adapted to be engaged by the lower end of a corresponding key stem on the downward movement of the latter when said levers are 10 shifted into operative relation with said key stems as later described.

Each shaft 222 is at all times under tension of an individual coil spring 228 tending to rotate it so as to send the free ends 15 of levers 227 toward the bottoms of the key stems, but this movement is limited, so as to normally hold said levers in the angular positions shown in Figs. 3 and 41, by stop pins 229 fast on shafts 222 engaging stationary pins 230 fast on frame 223. (See 20 Fig. 41.)

Frame 223 is shiftable so as to bring the free ends of all the levers 227 simultaneously into position beneath the key stems 2 25 so that the downward movement of any of said stems will operate its corresponding lever 227, or to simultaneously remove all said levers from the paths of said key stems so that the operation of any key will 30 have no effect on any of shafts 222. This shifting of said frame is effected by the rotation of a shaft 231 carrying sector gears 232 and 233 which mesh respectively with rack teeth cut on frame 223. Shaft 231 is 35 operated for this purpose by a lever 234 fast thereon and located at the front of the machine outside of the outer casing. By throwing lever 234 over against stop 235 (Fig. 34) frame 223 is shifted so as to bring 40 the free ends of all the levers 227 into position to be operated by the key stems 2, and by throwing lever 234 over against stop 236, frame 223 is shifted so as to remove said levers from alinement with the key stems 45 as shown in Fig. 41, so that said key stems may be operated without operating said levers.

For the purposes of the present description, it will be assumed that the typewriter 50 employed is any one of the several well known makes such as the Remington, Underwood or L. C. Smith.

The typewriting machine to be operated is supported upon four posts 237 on a rectangular frame 238 in which is mounted the immediate typewriter operating mechanism, said posts having reduced extensions or nipples 239 (see Fig. 40) which fit into cavities in the frame of the typewriter proper, thus 60 holding it against horizontal displacement.

Journaled in a series of fixed uprights 240 and in a vertical web on plate 241 of frame 238, are a plurality of rock shafts 242, extending each at one end through a side of 65 frame 238. The upright supports 240 are all

formed on a diagonally disposed bar 243 constituting a portion of frame 238.

There is a rock shaft 242 for each rock shaft 222, and these two sets of shafts are adapted to be positively coupled in axial 70 alinement by couplings comprising a wedge shaped member 244 on an end of each shaft 242, engaging a wedge-shaped opening in a coupling member 245 fast on an end of each shaft 222 outside of the outer casing of the 75 calculating machine.

The first or forward shaft of the series 242 carries a plurality of bell crank levers 246 separated by spacing collars 246^a, and each having a horizontal arm 247 and a 80 downwardly extending arm 248 (see Figs. 37, 38 and 40).

Each lever arm 247 is adapted to operate a digit key of the typewriter, and for this purpose there is rigidly attached to each 85 such key lever a depending strap 249 carrying near its bottom a pin or roller 250 adapted to be engaged by the respective lever arms 247 on the downward movement thereof to operate the typewriter levers.

Lever arms 247, as will be seen from Fig. 38, normally occupy a position some distance above their corresponding strap rollers 250. This produces a certain amount of lost motion between said arms and rollers 95 whereby the typewriter key bars are operated by a blow rather than a pull, thus getting the effect of striking the keys of the typewriter by the fingers, which is a considerable advantage. This not only compensates for the more or less gradual movement of the calculating machine keys, but it requires less force to be applied to the calculating machine keys to produce the same result on the typewriter.

It should also be observed that the strap connection between the typewriter key bars and the lever arms 247 permits of the operation of the typewriter digit keys independently of the calculating machine.

Arms 247 are operated each by a separate shaft of the series 242 and this is done in the following way: Arm 247 which operates the key lever for the numeral "1" (which is the letter "1" on a typewriter) is operated by the forward shaft 242 (Fig. 37) and is therefore fast to said shaft and need not have any depending arm 248. The other arms 247, however, are operated by shafts other than the one upon which they are supported, and this is effected by connecting the downwardly extending arms 248 each to its respective shaft 242 through a link 251 and a downwardly extending lever arm 252 fast on each of said shafts, said links being flexibly or pivotally connected to said arms.

Each shaft 242 is rotated, as described, against the tension of an individual coil spring 253, the backward movement of said shafts by said springs being limited by a

130

series of arms 254 fast on said shafts engaging with stop pins 255 on a frame 223. This, however, is merely a secondary function of arms 254. Their real or primary function is to operate the spacing mechanism of the typewriter. The spacing mechanism of all well known typewriters is operable in two ways; it is operable either from the space bar or from any key. Each key of such machines therefore performs two functions when struck. It operates to send the corresponding type against the paper, and it also operates the spacing mechanism. In performing the latter function, a considerable resistance has to be overcome, and this resistance occurs just before the type reaches the paper. This is readily perceptible if one will depress a typewriter key slowly until the type is brought against the paper.

If on the other hand, the space bar be depressed simultaneously with a key, this resistance will not be felt and the type will proceed toward the paper with an entirely unimpeded movement, the reason for which is that the releasing of the spacing mechanism is effected by the operation of the space bar and the key lever has no other work to do but to send the type against the paper.

This extra load, or resistance to the operation of the key levers, is not so material a consideration when the keys are operated by a direct blow, but it is material when operating the key levers of the typewriter from the keys of a calculating machine, which latter are not operated with the quick sharp blows used on the typewriter keys when directly operated, and which also act upon the key levers of the typewriter through considerable intermediate mechanism, in addition to operating the dials.

My invention therefore embodies means to operate the space bar lever, or its equivalent, of the typewriter each time one of the key levers is operated in order to remove the usual resistance to the travel of the type bar.

This is effected in the present case by causing each of the arms 254, on the operation of its shaft 242, to act through one of a series of pins 256 to shift longitudinally a bar or link 257 pivotally connected to a lever arm 258 fast on a rock shaft 259 having another arm 260 fast thereto, which is flexibly connected to the space bar 261 of the typewriter. Therefore, when any of the rock shafts 242 is operated by any of the keys of the calculating machine, it will shift bar 257 to the right (Fig. 39) and operate the space bar of the typewriter.

The spacing mechanism of the typewriter may, however, be operated in the usual way from space bar 261, independently of the calculating machine, since bar 257 may move to the right (Fig. 39) independently of the connection with the calculating machine.

I do not here claim any special kind of

typewriter spacing mechanism, so it is not considered necessary to show any more than the well known space bar 261 and levers 262 therefor for operating any of the well known forms of such mechanism.

Nor has it been attempted to indicate any of the type printing mechanism of a typewriter. In Figs. 37 and 38 are shown the digit keys 263 with portions of their key levers 264, which is sufficient to show how any of the well known typewriters are operated.

In Fig. 34 is shown the general outline of a typewriter 265 as it appears coupled to my calculating machine, the digit keys and space bar of the typewriter being shown in full lines, and the other keys of the typewriter in dotted lines.

The typewriter supporting frame 238 may be provided with a thin metal flange or side 85 casing 266 into which extends the lower portion of the typewriter frame. In Fig. 37, 267 indicates the lower portion of the typewriter frame.

For the purpose of holding the typewriter 90 supporting frame and the calculating machine in proper alinement, there may be secured to the side of said frame adjacent the calculating machine two brackets 268 (see Figs. 35 and 36) each having an upturned 95 conical lug 269, adapted to fit respectively into two conical cavities 270 in the base of the calculating machine, said cavities being preferably provided with a metal lining 271.

My calculating machine in combination 100 with a typewriter, as here shown, is particularly useful for billing, trial-balance, debit and credit statements, listing checks, etc., but I do not limit my invention to any particular use. Nor is it believed to be necessary to describe in detail any of these operations as performed upon my machine. It is sufficient to say that the machine here presented permits the typewriter to be operated from its own keys to perform any of its normal functions while coupled to the calculating machine; that the digit of any calculating machine key may be recorded on the typewriter by the operation of said key, and that the typewriter and calculating machine may be readily connected and disconnected from each other to permit the calculating machine keys to be operated without operating the typewriter; as, for example, to secure a result to be subsequently recorded on the typewriter.

It might be well, however, at this point, to more fully explain the function of dial 29 to "verify" and "prove" results recorded on the typewriter, to which reference has heretofore been made. Suppose, for example, the calculating machine keys have been operated to add a series of items. In the process of adding these items, the separate items may be listed on a bill in the typewriter by

striking the calculating machine keys, in the process of addition, during which time the typewriter and calculating machine are connected. The result of this addition will show on the dials 27 of the calculating machine, and the separate amounts will show in typewriting on the bill in the typewriter. In printing the total on the bill in the typewriter by the manipulation of the keys of the calculating machine, the dials 27 are shifted so that by the time the total is recorded on the typewriter, these dials show an entirely different amount, so that if it be desired to verify or compare the amount of the total printed by the typewriter with the total as originally shown by dials 27, this cannot be done with said dials alone. By providing dials 29, however, which may be coupled to dials 27 during the operation of securing the total, and uncoupled therefrom during the operation of printing the total, we thus have means for "holding" the total independently of the manipulation of the keys of the calculating machine in recording the total, and by comparing the total as recorded on the typewriter with that shown by the dials 29, we may thus verify the record. In other words, one may in this way be sure that in recording the total, he struck the proper keys of the calculating machine.

While I have herein shown and described certain specific constructions, it should be understood that various changes and modifications may be made in these without departing from the true spirit of my invention.

What I claim is:

1. A calculating machine, comprising a key operated rock shaft, a rotatable dial shaft and a number dial operated thereby, means to rotate said dial shaft from its key operated rock shaft, and key operated locking means acting upon said dial shaft to lock the same against overthrow by said rock shaft.

2. In a calculating machine, in combination, a key-operated master rock shaft, a rotatable dial shaft and number dials operated thereby, means to rotate said dial shaft from said key-operated rock shaft, a supplementary rock shaft associated with said master rock shaft, means to lock said dial shaft from overthrow by said master rock shaft, and key operated means to rotate said supplementary rock shaft to operate said locking means.

3. A calculating machine, comprising a key-operated master rock shaft, a rotatable dial shaft and a number dial operated thereby, means to rotate said dial shaft from its key operated rock shaft, a stop ratchet fast on said dial shaft, a supplementary rock shaft, a stop lever fast on said supplementary rock shaft, and key-operated means

to rotate said supplementary shaft to cause interlocking of said stop lever and ratchet to prevent overthrow of said dial shaft.

4. A calculating machine, comprising a rock shaft, a plurality of keys adapted to operate said rock shaft, a rotatable dial shaft and a number dial operated thereby, means to rotate said dial shaft from said key operated rock shaft, a stop ratchet fast on said dial shaft, a supplementary rock shaft, a stop lever fast on said supplementary shaft, a plurality of arms fast on said supplementary shaft, and means carried by said keys to engage and operate said arms to cause interlocking of said stop lever and ratchet, in order to prevent overthrow of said dial shaft from the operation of said keys.

5. A calculating machine, comprising a plurality of dial shafts and number dials mounted thereon, means to rotatably support said shafts at two points, a sleeve surrounding each of a plurality of said shafts and out of contact therewith, and carrying escapement mechanism rotatable on said sleeve, for operating the shafts passing therethrough.

6. A calculating machine, comprising a plurality of dial shafts and number dials operated thereby, means to rotatably support said shafts, a sleeve bearing surrounding each of a plurality of said shafts but out of contact therewith, an escapement ratchet rotatable on each of said sleeves, means to connect each of said ratchets to its respective dial shaft, a gear also rotatable on each of said sleeves, a spiral spring encircling each of said sleeves and attached to said ratchet and gear thereon, means to rotate said gears from the dial shafts of the next lower denomination to wind up said springs, means normally restraining the rotation of said escapement ratchets by said springs in unwinding, and means operated by the dial shaft of the next lower denomination to release said restraining means.

7. A calculating machine, comprising a plurality of dial shafts and number dials operated thereby, means to rotatably support said shafts at two points, a sleeve surrounding each of a plurality of said shafts but out of contact therewith, couplings having two relatively movable members, one fixed to each of said shafts, and the other rotatable on each of said sleeves, a gear also rotatable on each of said sleeves, a spiral spring encircling each of said sleeves and attached to the coupling member and gear thereon, means to rotate said gears from the dial shaft of the next lower denomination to wind up the said springs, means normally restraining the coupling member attached to said springs from rotation by said springs in unwinding, and means operated by the dial shaft of the next lower denomination

to release said restraining means to permit said springs to rotate said dial shafts through said couplings.

8. A calculating machine, comprising a plurality of key operated rock shafts, a plurality of rotatable dial shafts and number dials operated thereby, means to rotate said dial shafts individually from their respective key-operated rock shafts, mechanism for carrying from a lower to a higher order of dials, a locking lever and means coöperative therewith to prevent overthrow of said dial shafts in carrying, and means carried by the respective key-operated rock shafts and operative by the rotation thereof from their respective keys, to release the locking lever of a corresponding dial shaft from the overthrow dial locking means thereof.

20 9. A calculating machine, comprising a plurality of rotatable dial shafts and number dials operated thereby, mechanism for carrying from a lower to a higher order of dials, a stop ratchet fast on each of said shafts subject to carrying from a shaft of lower denomination, a stop pawl for each of said ratchets adapted to coöperate therewith to prevent overthrow of the dial shafts in carrying, and a cam on each of said dial shafts adapted to release the stop pawl of the next higher denomination, and means to return each of said stop pawls to engage its corresponding ratchet in time to prevent overthrow of the dial shaft on which said ratchet is mounted.

35 10. A calculating machine, comprising a plurality of key operated master rock shafts, a plurality of rotatable dial shafts and number dials operated thereby, means to rotate said dial shafts individually from their respective key-operated rock shafts, a plurality of supplementary rock shafts, one for each of said master rock shafts, mechanism for carrying from a lower to a higher order of dials, locking means mounted on said supplementary shafts but rotatable independently thereof, means coöperative with said locking means to prevent overthrow of said dial shafts in carrying, means also on said supplementary shafts to operate said locking means, and means carried by the respective dial shafts and operative by the rotation thereof from their respective keys, to operate the lock operating means carried by said supplementary shafts to release the overthrow dial locking means.

40 11. A calculating machine, comprising a plurality of key operated master rock shafts, a plurality of rotatable dial shafts and number dials operated thereby, means to rotate said dial shafts individually from their respective key-operated rock shafts, a plurality of supplementary rock shafts, one for each of said master rock shafts, mechanism for carrying from a lower to a higher

order of dials, a stop lever mounted on each of said supplementary shafts but rotatable independently thereof, a stop ratchet fast on each of the carrying dial shafts and coöperative with said stop levers to prevent overthrow of said shafts in carrying, a second lever rotatably supported upon each of said supplementary rock shafts and operatively connected to the stop lever on the same shaft therewith, and means carried by the respective dial shafts and operative by the rotation thereof from their respective keys, to operate the said levers to release the stop ratchets corresponding thereto.

45 12. A calculating machine, comprising a rotatable dial shaft and means to operate the same, one or more number dials fast on said shaft, a stationary collar bearing encircling said shaft but out of engagement therewith, a supplementary number dial rotatably mounted on said collar bearing, and means to couple and uncouple said supplemental dial to and from said dial shaft at will.

50 13. A calculating machine, comprising a rotatable dial shaft and means to operate the same, a number dial fast on said shaft, a supplementary number dial encircling said shaft but normally disengaged therefrom, and means to couple and uncouple said supplementary dial to and from said dial shaft.

55 14. A calculating machine, comprising a dial shaft, a number dial for said shaft and rotatable with respect thereto, mechanism to couple said dial to said shaft and uncouple the same, and means operable by the uncoupling means to resist the rotation of said dial when uncoupled from said shaft.

60 15. A calculating machine, comprising a dial shaft, a number dial, rotatable with respect thereto, mechanism to couple said dial to said shaft and uncouple the same, and a friction shoe operable by the uncoupling means to resist the rotation of said dial when uncoupled from said shaft.

65 16. A calculating machine, comprising a series of dial shafts and means to rotate the same, a number dial on and operated by each of said shafts, a pinion rotatable on and slidable longitudinally of each of said shafts, means to couple and uncouple said pinions to and from their respective shafts by the movement of said pinions longitudinally of said shafts, a rack meshing with the several said pinions, a shiftable frame carrying said rack, lever operated means to shift said frame to couple and uncouple said pinions to and from their respective dial shafts, gearing for shifting said rack to rotate said pinions, and lever operated means for operating the last named gearing.

70 17. A calculating machine, comprising a plurality of dial shafts and means to rotate the same, a number dial fast on each of said

shafts, a registering dial for each of said shafts but normally disengaged therefrom, a pinion rotatable on each of said shafts and slideable thereon between the two said 5 dials of each shaft, means to couple said pinion with either of the dials on the same shaft therewith, lever operated means adapted to shift all of said pinions longitudinally of said shafts to effect said coupling, and lever operated means to simultaneously 10 rotate all said pinions to reset the dials coupled thereto.

18. A calculating machine, comprising a series of dial shafts and number dials operated thereby, keys, and mechanism for operating said dial shafts from said keys, mechanism operable by said keys to prevent overthrow of said shafts, mechanism to reset said dials, and mechanism operated by 15 the resetting mechanism to operate said key operated overthrow mechanism to prevent overthrow of said dials in resetting.

19. A calculating machine, comprising a series of columns of keys, a number dial 20 for each of said columns, means operable by the keys of any column to operate the dial corresponding to that column, carrying mechanism to operate said dial from the column of keys of the next lower order, 25 mechanism to lock said dial from overthrow both in carrying and when operated by keys of the same order, mechanism to reset said dials, and mechanism operated by the resetting mechanism to operate said locking 30 mechanism to unlock said dials for resetting.

20. A calculating machine, comprising a plurality of number dials, and key operated means to operate said dials, dial resetting mechanism, lever operated means to 40 couple said resetting mechanism to said dials, means to operate said coupling means, mechanism to carry from a lower to a higher order of dials, a series of levers and means coöperating therewith to lock said dials 45 against overthrow in carrying, a shiftable bar having a series of pins adapted to operate the respective locking levers to unlock said dials for resetting, and means for shifting the said bar by the operation of 50 said coupling reset lever.

21. A calculating machine, comprising a series of rotary dial shafts and number dials mounted thereon for operation thereby, mechanism for carrying from a lower to a 55 higher order of said shafts, a stop ratchet fast on each of said shafts subject to said carrying operation, a series of levers each having a yielding nose adapted to engage respectively with one of said ratchets to 60 prevent overthrow of its dial shaft in carrying, a cam on each dial shaft adapted to withdraw the ratchet holding lever of the dial shaft of the next higher denomination from its ratchet to free said dial shaft, and 65 a spring acting to return the nose of said

lever to its stop ratchet an instant preceding the operation of carrying.

22. In a calculating machine having a plurality of rotary dial shafts, number dials carried on and operated thereby, and mechanism for rotating said shafts to carry from the one of next lower denomination, means for preventing the overthrow of said shafts in carrying, comprising a stop ratchet fast on each of said shafts subject to carrying operation, and a stop lever for each of said ratchets having a pawl yieldably mounted thereon and forming a nose adapted to be projected by said lever into the path of the teeth of said ratchet to stop the rotation thereof.

23. A calculating machine, comprising a plurality of dial shafts and one or more number dials carried thereby, and means to reset said number dials, said resetting means comprising coupling means rotatable on and slideable longitudinally of each of said shafts, means fast to each of said shafts and coöperative with the coupling means thereon to rotate the shaft, means common to all of said slideable coupling means to simultaneously rotate the same and also to simultaneously shift the same longitudinally of said shafts, a lever and mechanism operated thereby to shift said means common to all of said slideable couplings, longitudinally of said shafts, and a lever and means operative thereby to operate the coupling rotating means to rotate said coupling means.

24. A calculating machine, comprising a plurality of rotary dial shafts and number dials carried thereby, a stop ratchet fast on each of said dial shafts, a locking lever individual to and coöperative with each of said ratchets for preventing overthrow of said shafts, a bar shiftable with respect to said shafts, a series of pins secured to said bar and adapted each to operate upon a different one of said locking levers, rock 105 shaft operated dial resetting mechanism, and operative connection between the rock shaft of the resetting mechanism and said bar to shift the same on the operation of the resetting mechanism to lock said dial shafts 110 against overthrow.

25. A calculating machine having two sets of number dials, a series of dial shafts on each of which is mounted fast a dial of each of said sets, lever operated dial resetting 120 mechanism common to both sets of dials, and means to limit the movement of said lever to a shorter stroke in resetting one set of dials than in resetting the other set, said means comprising a fixed stop adjacent the 125 path of the travel of said lever and an adjustable stop on said lever.

26. A calculating machine having two sets of number dials, a series of dial shafts on each of which is mounted fast a dial of 130

each of said sets, lever operated dial resetting mechanism common to both sets of said dials, and means to limit the movement of said lever to a shorter stroke in resetting one set of dials than in resetting the other set, said means comprising a fixed stop adjacent the path of the travel of said lever and an adjustable stop on said lever, comprising a spring pressed pin located in the handle of said lever and adapted to be protruded therefrom, at the will of the operator, into the path of said fixed stop.

27. A calculating machine, comprising a dial shaft, a sleeve encircling said dial shaft but out of engagement therewith, a number dial mounted for rotation on said sleeve, and mechanism to effect driving connection between said shaft and said dial.

28. A calculating machine, having a plurality of dial shaft units, each comprising a dial shaft, one or more dials mounted thereon, and power mechanism encircling said shaft for rotating the same to carry from a dial shaft to the next lower denomination, all of said parts being free to be lifted from said machine together as a unit.

29. A calculating machine, comprising a plurality of dial controlling rock shafts, and adjustable tension means for said shafts, said means comprising a ratchet loose on each of said shafts, a coil spring individual to each of said shafts and fixed thereto and to the respective ratchets, and a holding pawl individual to each of said ratchets.

30. A calculating machine, comprising a column of keys, a rotary dial shaft, operative connection between said keys and shaft, a plurality of number dials each of which is adapted to perform a different function from the other, two of said dials being mounted fast on said dial shaft and one of said dials rotatable with respect to said shaft, and means to connect and disconnect the last mentioned dial to and from said dial shaft at will.

31. A calculating machine, comprising a rotary dial shaft and means to rotate the same, an addition and multiplication number dial and a division and subtraction number dial fast to said dial shaft, an auxiliary dial rotatable with respect to said dial shaft, and means to couple said auxiliary dial to said shaft at will.

32. A calculating machine having quotient counting dial indicating mechanism comprising one or more number dials, an actuating pawl individual to each of said dials, a latch connected to each of said dials for operating the same, an actuator common to all said latches, a striker bar operatively connected to said actuator and arranged to form a part of the keyboard of the machine, means to bring said latches into operative relation with said actuator successively and means to reset all of said dials simultaneously.

33. A calculating machine having quotient counting dial indicating means comprising a plurality of number dials, an actuating pawl individual to each of said dials, a latch connected to each of said dials for operating the same, an actuator common to all said latches, a striker bar operatively connected to said actuator and arranged to form a part of the keyboard of the machine, means to bring said latches into operative relation with said actuating bar successively, a knob for operating the last mentioned means and provided with means to indicate the number set for operation by said striker bar.

34. A calculating machine, comprising a plurality of keys, in combination with a plurality of rock shafts operative by said keys, shiftable supporting means for said rock shafts to bring the same into and out of operation relative to said keys, typewriter operating means, and means to effect operative connection between the typewriter operating means and said rock shafts.

35. A calculating machine, comprising a plurality of keys, in combination with a plurality of rock shafts having arms operable by said keys to rotate said shafts, a supporting frame for said rock shafts shiftable to bring said arms into and out of operation relative to said keys, typewriter operating means, and means to effect operative connection between the typewriter operating means and said rock shafts.

36. A calculating machine, comprising a plurality of keys, in combination with a plurality of rock shafts operative by said keys, shiftable supporting means for said rock shafts to bring the same into and out of operation relative to said keys, means to effect operative connection between the typewriter operating means and said rock shafts, typewriter operating means comprising a plurality of rock shafts and operative connection between said rock shafts and the key bars of the typewriter, and means operative by the shifting of said shiftable supporting means to couple and uncouple said key operating rock shafts and the typewriter operating rock shafts to and from each other.

37. A calculating machine, comprising a plurality of dial controlling keys, and a set of rock shafts operable by said keys, in combination with a frame, a set of rock shafts mounted in said frame, a plurality of pivoted arms operable by the last named rock shafts, a typewriter having key bars operable by said arms, and means to couple and uncouple said two sets of rock shafts to and from each other.

38. A key controlled calculating machine, in combination with a typewriter and mechanism for operating the typewriter from the keys of the calculating machine, said mechanism comprising a frame upon which the typewriter is adapted to rest, a series of rock

- shafts supported in said frame, a member
pendant from each of the digit key levers
of the typewriter, a lever individual to each
of said rock shafts and operable thereby to
5 strike each a separate one of said pendant
members to operate the corresponding digit
key levers of the typewriter, and operative
connection between the keys of said calcu-
lating machine and said rock shafts.
- 10 39. A key controlled calculating machine
in combination with a typewriter having
spacing mechanism and recording mecha-
nism and means operative by a single stroke
of a calculating machine key to independ-
15 ently operate both the spacing and recording
mechanisms of the typewriter.
40. A key controlled calculating machine,
in combination with a typewriter having key

operated recording mechanism and spacing
mechanism, operative connection between the 20
digit keys of the calculating machine and
corresponding digit key levers of the type-
writer, and additional operative connection
between the digit keys of the calculating
machine and the spacing mechanism of the 25
typewriter, whereby a single stroke of any
calculating machine key independently op-
erates the spacing and recording mechanisms
of the typewriter.

In testimony whereof I affix my signature 30
in presence of two witnesses.
